UNITED STATES PATENT OFFICE.

DIXON F. LYNCH, OF MONTICELLO, GEORGIA.

PLIERS.

1,331,443.

Specification of Letters Patent.

Patented Feb. 17, 1920.

Application filed June 20, 1919. Serial No. 305,529.

To all whom it may concern:

Be it known that I, DIXON F. LYNCH, a citizen of the United States, residing at Monticello, in the county of Jasper and 5 State of Georgia, have invented new and useful Improvements in Pliers, of which the following is a specification.

This invention relates to pliers and has for its object the provision of novelly 10 constructed pliers in which powerful leverage may be obtained, in which the jaws will remain substantially parallel in their movement, and which is provided with springs for normally holding the jaws closed.

15 An important object is the provision of pliers of this character provided at one side with wire cutting means having novel means for its actuation, this wire cutting means being operated automatically upon movement of the handles of the pliers.

Another object is the provision of pliers of this character which are so constructed and arranged that wires may be spliced thereby, the springs above referred to being 20 of particular advantage in holding the jaws closed while splicing is effected.

An additional object is the provision of pliers of this character which will be simple and inexpensive in manufacture, highly 25 efficient in use, durable in service, and a general improvement in the art.

With the above and other objects and advantages in view, the invention consists in the details of construction to be hereinafter 35 more fully described and claimed, and illustrated in the accompanying drawings, in which—

Figure 1 is an elevation of the pliers showing the jaws in closed position,

40 Fig. 2 is a similar view showing the jaws in open position,

Fig. 3 is a longitudinal sectional view showing the jaws open and the wire cutting device also open,

45 Fig. 4 is an edge elevation,

Fig. 5 is a detail sectional view taken through the wire splicing features, and

Fig. 6 is a detail perspective view of one of the plier jaws.

50 Referring more particularly to the drawings, the numerals 10 and 11 designate the handles which may be bifurcated at one end to provide crossed arms 12 which are pivotally connected by a suitable bolt or the like 13. Disposed between the arms 12 of the handles 10 and 11 are jaws 14 which

are pivotally connected, as shown at 15, with the handles at points spaced from the pivot bolts 13. The ends of the arms 12 carry bolts 16 which extend through slots 17 in 60 the jaws 14 so that when the handles 10 and 11 are moved apart the jaws 14 will also be moved apart, the provision of the slots 17 preventing binding. A pair of leaf springs 18 are disposed between the handles 65 and are secured thereto at one end and have their other ends engaged within a slot 19 in the pivot bolt 13. By this construction it will be seen that the handles and jaws will be normally held together or in closed 70 position.

The jaws 14 are provided upon their engaging faces with mating semicylindrical grooves 20 and the meeting faces of the jaws between the grooves and the extremities of 75 the jaws are preferably roughened to prevent slipping of the jaws when engaged upon an article. The bolt 16 which connects the free end of the arm 12 of the handle 10 with the intermediate portion of one 80 of the jaw members carries a grooved pulley or roller 21 and this same jaw 14 is provided adjacent the pulley 21 with a stud 22 and the arrangement of parts is such that the cylindrical opening formed by the mat- 85 ing grooves 20 is disposed between but at a little distance from the pulley 21 and stud 22. The provision of the grooves 20, pulley 21, and stud 22 enables the device to be used in splicing wires, the wires being 90 brought through the holes formed by the meeting grooves and suitably engaged with the pulley and stud whereby upon rotation of the device the wires will be twisted together. 95

In order that the device may be used for cutting wire I provide the jaw member 14 opposite the one provided with the splicing devices, with a longitudinally extending recess 23 and disposed within this recess are 100 two members 24 and 25, the former of which is pivoted upon the pivot bolt 15 passing through the associated jaw and the latter of which is provided with a hole pivotally receiving the bolt 16 which connects 105 the associated jaw with the ends of the arms 12 carried by the handle 11. Each of the members 24 and 25 is partly cut away and they are superposed with these cut away portions in engagement and is pivotally 110 connected, as shown at 26. By the cutting away or recessing of the members 24 and

25, it will be seen that their outer sides will be flush. The members 24 and 25 are provided with cutting blades 27 formed integrally thereon and adapted to sever wire.

5 In the use of the pliers it will be seen that they are used as pliers in the ordinary manner, the positions of the jaws being controlled by proper manipulation of the handles. Owing to the peculiar connection of 10 the wire cutting members with the remainder of the pliers, it will be seen that when the handles 10 and 11 are moved apart for opening the jaws 14, the members 24 and 25 will be moved upon their pivot point 26 15 and the blades 27 will be separated whereby a wire to be cut may be inserted therebetween. When the handles are subsequently brought together the blades 27 will obviously sever the wire. The use of the 20 device as a wire splicer has already been described and it is believed needs no further explanation.

From the foregoing description and a 25 study of the drawings it will be apparent that I have thus provided a comparatively simple and inexpensive pliers which will be effective as pliers, inasmuch as means have been provided for insuring powerful leverage for gripping and holding material or 30 an article and with which is associated novelly constructed means for severing wire, the device being furthermore equipped with

means for splicing wires so that the device will be highly efficient and labor saving in general use and particularly for use in constructing or repairing telegraph and telephone wires.

35

While I have shown and described the preferred embodiment of my invention, it is of course to be understood that I reserve the 40 right to make such changes in the form, construction, and arrangement of parts as will not depart from the spirit of the invention or the scope of the subjoined claims.

Having thus described my invention, I 45 claim:

1. Pliers comprising a pair of handles bifurcated at one end to provide spaced arms arranged in crossed relation and pivotally connected, the pivot bolt being provided with a slot, jaws carried by said arms, and a pair of leaf springs disposed between said handles and secured thereto at one end and having their other ends engaging with in the slot in said pivot bolt.

50

2. Pliers comprising a pair of handles arranged in crossed relation and terminating in jaws, a bolt pivotally connecting said handles at their point of crossing and provided with a slot, and a pair of leaf springs 60 secured to said handles and engaging within said slot.

55

In testimony whereof I affix my signature.

DIXON F. LYNCH.
